FIREARM

Edwin H. Johnson, Dayton, Ohio, assignor to The
Kilgore Mfg. Company, Tipp City, Ohio, a cor-
poration of Ohio

Application July 20, 1942, Serial No. 451,591

9 Claims. (Cl. 42—1)

This invention relates to firearms adapted for discharging flares for use in signaling or lighting purposes.

An object of the invention is to provide a fire-arm that is constructed and arranged to receive a signal or illuminating flare through the muzzle or the breech of the firearm.

Another object of the invention is to provide a firearm having a short smooth-bore barrel adapted to receive a signal or illuminating flare through the muzzle or through the breech thereof, which flare is constructed and arranged in a manner that it forms an auxiliary or detachable barrel extending beyond the barrel of the firearm.

Another object of the invention is to provide a firearm constructed and arranged to receive a flare through the muzzle or breech thereof, the operating mechanisms of the firearm being so arranged that they can be operated with one hand.

Another object of the invention is to provide a firearm adapted to receive fixed ammunition either through the muzzle or the breech thereof.

Another object of the invention is to provide a combination muzzle loaded and breech loaded firearm constructed and arranged for one hand operation when being used with either muzzle loaded or breech loaded fixed ammunition.

Another object of the invention is to provide a combination muzzle loaded and breech loaded firearm having a single mechanism for retaining muzzle loaded ammunition within the barrel of the firearm and for ejecting breech loaded ammunition.

Another object of the invention is to provide a combination muzzle loaded and breech loaded firearm for discharging signal or illuminating flares that is constructed and arranged for convenient operation with a heavy gloved hand, such as aviators' gloves.

Another object of the invention is to provide a low pressure firearm for discharging signal flares that is constructed and arranged to be used selectively as a muzzle loaded firearm or a breech loaded firearm without interfering with the functions of either type of firearm.

Further objects and advantages will become apparent from the drawings and from the following description.

In the drawings:

Figure 1 is a cross-sectional view of the firearm of this invention showing a breech loaded flare therein.

Figure 2 is an elevational view of the firearm showing extraction of a breech loaded flare.

Figure 3 is an enlarged cross-sectional view of a portion of the mechanism of Figure 1 showing the extracting mechanism.

Figure 4 is an enlarged cross-sectional view similar to Figure 3 but showing the extracting mechanism in position when ejecting a breech loaded flare.

Figure 5 is a partial cross-sectional view of the firearm showing a muzzle loaded flare being inserted into the barrel, with the flare in cross-section.

Figure 6 is a partial cross-sectional view of Figure 5 showing the latch for retaining the muzzle loaded flare within the barrel.

Figure 7 is a cross-sectional view similar to Figure 6 showing the latch mechanism released from a muzzle loaded flare so that the same can pass outwardly through the muzzle.

Figure 8 is a transverse cross-sectional view of the firearm taken along line 8—8 of Figure 5.

Figure 9 is a transverse cross-sectional view similar to Figure 8 showing the flare releasing mechanism in position for releasing a muzzle loaded flare.

Figure 10 is a cross-sectional view of the latch-extractor mechanism as viewed upwardly from the bottom thereof and taken along line 10—10 of Figure 6.

Figure 11 is a cross-sectional view of a mount for the firearm of this invention and shows the barrel of the firearm positioned within the mount.

Figure 12 is an elevational view of the manner of preparing the firearm for receiving a muzzle loaded flare.

Figure 13 is an elevational view showing the manner in which the flare is picked up through the muzzle of the firearm.

Figure 14 shows the firing position of the firearm with a muzzle loaded flare therein.

Figure 15 is an elevational view of a firearm showing the manner of operation for discharging a muzzle loaded flare.

Figure 16 is an elevational view of the firearm showing the manner of breaking the breech of the firearm in order to place a breech loaded flare therein.

Figure 17 is an elevational view showing the manner of loading a breech loaded flare.

Figure 18 is an elevational view showing the manner of operation of the firearm for closing the breech thereof with a flare therein using only one hand.

Figure 19 is an elevational view showing the firing position of the firearm with a breech loaded flare therein.

Figure 20 is an elevational view showing the operation of the firearm for extracting a breech loaded flare.

Figure 21 is an elevational view showing the insertion of the firearm in a mount.

Figure 22 is an elevational view showing the manner of breaking the breech of the firearm by a gloved hand.

Figure 23 is an elevational view showing the insertion of a breech loaded flare with a gloved hand.

Figure 24 is an elevational view showing the closing of the breech of the firearm with a gloved hand.

Figure 25 is an elevational view showing removal of the firearm from the mount by means of a gloved hand.

The firearm of this invention consists of a frame 10 having a chamber 11 within which the firing mechanism is placed, and a handle 12. A smooth-bore barrel 13 is pivoted upon an extension 15 of the frame 10. The barrel 13 is open at both ends thereof and when in firing position the rear end of the barrel 13 is closed by a breech wall 16. A latch member 17 is pivoted upon the barrel 13 by means of a pivot pin 18 extending through ears 19 and cooperates with a strike 20 for securing the barrel 13 in firing position with the rear end thereof in engagement with the breech wall 16. A spring 21 urges the latch 17 downwardly to hold the same in engagement with the strike 20.

A stop 22 controls the downward movement of the latch 17. The rear end of the latch 17 is provided with an upwardly inclined extension 23 that is disposed at a substantial angle to the wall of the breech of the firearm so that a gloved hand can readily release the latch 17 from the strike 20 and so that the hand operating the firearm can readily reach the latch 17 to release the same when the bare hand is used for operating the firearm.

The firing mechanism of the firearm consists of a hammer 24 constructed from a pair of side members 25 pivoted upon a cross pivot pin 26 and spaced at their lower ends upon the cross pivot pin 26 by means of a sleeve 27. The members 25 are secured at their upper ends by means of a bridge 28. A firing pin 29 extends through the hammer 24 and has the rear end thereof extending from the hammer 24 to provide a locating pin 30 for one end of a spring 31. The opposite end of the spring 31 engages a cap 32 that closes the chamber 11. In order to operate the hammer 24 a dog 33 is pivoted between the side members 25 by means of a pivot pin 34. The dog 33 has a stop 35 on one end thereof and an actuating cam 36 on the opposite end. A stop 37 is provided between the side members 25 of the hammer 24 against which the dog stop 35 rests when the firing mechanism is in released position, and is retained against this stop 37 by means of a spring 38.

A trigger 39 is pivoted to the frame by a pivot pin 40 and has a cam 41 thereon adapted to engage the dog cam 36. A wire spring 42 encircles a pin 43 and has one end thereof in engagement with the trigger 39 to urge the same forwardly until a stop 44 engages the edge of the slot 45 through which the trigger extends into the chamber 11.

The opposite end 46 of the spring 42 encircles a pin 47 and engages a safety latch 48 pivoted upon the pin 47. The safety latch 48 has a forwardly extending face 49 placed in the path of

travel of an angular face 50 provided on the hammer supporting members 25 so that the hammer 24 cannot be moved rearwardly as long as the safety latch 48 is extended outwardly (as shown in Figure 1).

To fire a projectile placed within the barrel 13 the trigger 39 is pulled rearwardly (as shown in Figure 1) and at the same time the safety latch 48 is squeezed inwardly so that the face 49 of the safety latch is moved out of the path of travel of the face 50 on the hammer supporting members 25. The trigger cam 41 engages the dog cam 36 and forces the same upwardly and rearwardly against the compression of the spring 31 until the ends of the two cams meet, at which time the dog cam 36 will snap over the trigger cam 41 to release the hammer 24.

The firearm of this invention is adapted for discharging signal or illuminating flares of relatively large diameter. Therefore, the firearm can be referred to as a low pressure firearm as compared to a high pressure firearm of the type wherein a high speed projectile is discharged therefrom. There are two types of signal or illuminating flares that are in current use. One of the flares is adapted for breech loading and the other is adapted for muzzle loading. In Figures 1 to 4 inclusive the firearm is shown as used in combination with a breech loaded flare, while in Figures 5 to 10 inclusive the firearm is used in combination with a muzzle loaded flare.

It is necessary to provide some means for retaining a muzzle loaded flare within the barrel of the firearm until after the flare has been discharged, after which the flare cartridge can be released from the muzzle. Also, some means must be provided for extracting a breech loaded type of flare after the same has been discharged. In this invention the firearm is constructed and arranged with a single mechanism that produces both functions, namely, retaining a muzzle loaded flare within the barrel of the firearm and subsequently releasing the same as well as extracting a breech loaded type of flare.

The mechanism for accomplishing both functions in this combination muzzle loaded and breech loaded firearm consists of a latch-extractor 51 that is slidably disposed between a pair of ears 52 and 53 extending downwardly from the barrel 13. The latch extractor 51 has an upwardly extending ear 54 which passes through a slot 55 provided in the barrel 13 adjacent the breech wall 16. This ear 54 provides means for engaging a muzzle loaded flare to retain the same within the barrel and for extracting a breech loaded flare from the barrel in a manner to be hereinafter described.

The forward end of the latch-extractor 51 is provided with a downwardly extending ear 56 which is adapted to be engaged by a tongue 57 provided on the extension 15 of the frame 10 when the barrel 13 is pivoted upon the pin 14.

A pin 58 extends between the ears 52 and 53 and is in engagement with the lower face of the latch-extractor 51 so that the cooperation of the pin 58 with the face 59 provides a fulcrum for the latch-extractor 51. A wire torsion spring 60 encircles a pin 61 and has both ends thereof engaging the lower face of the latch-extractor 51 to urge the same upwardly against a pin 62 slidably disposed between the ears 52 and 53. A transverse pin 63 limits the downward travel of the latch-extractor 51.

The pin 62 is provided with a small diameter

portion 63 and a large diameter portion 64 slideable respectively in the ears 52 and 53. The pin 62 carries buttons 66 and 67 on opposite ends thereof for sliding the pin transversely with respect to the barrel 13 so that either the small diameter portion 63 or the large diameter portion 64 will engage the latch-extractor 51.

When the small diameter portion 63 of the pin 62 is adjacent the latch-extractor 51 the torsion spring 60 urges the latch-extractor against the small diameter portion 63 so that the extending arm 54 will enter the interior of the barrel 13. When the large diameter portion 64 engages the latch-extractor 51 the extending ear 54 thereof is disposed with the upper face in flush relationship to the inner surface of the barrel 13.

The barrel 13 may be placed within a suitable mount if it should be desirable to support the firearm rigidly when discharging a projectile therefrom. A mount can be provided in any suitable wall of a craft or vehicle so that the projectile can be discharged within the interior of the craft or vehicle and the flare will be discharged outwardly thereof. Such a mount is shown in Figure 11 wherein a wall 68 of a craft or vehicle is provided with a sleeve 69 having a bore 70 adapted to receive the barrel 13 of the firearm. The barrel 13 of the firearm is provided with a plurality of protrusions 71 spaced radially about the same which is adapted to enter slots 72 provided in the amount 69. The slots 72 terminate in a series of annular slots 73 disposed at a slight angle transversely of the bore 70 so that the cooperation of the slots 73 and the protrusions 71 form a bayonet type connection for the firearm.

A latch 74 is slidably mounted upon the barrel 13 and is retained in position by means of a confining wall 75. A compression spring 76 is contained within the latch 74 and has one end thereof held stationary by means of a stud 77. The spring 76 therefore urges the latch forwardly with respect to the forward end of the barrel 13. This latch is adapted to engage a slot 78 provided in the end wall of the mount 69 to prevent the firearm from rotating in the mount when in firing position.

The firearm just described is particularly adaptable for use in discharging signal flares from aircraft, or water craft, or for signaling between troops. The flares discharged from the firearm can be either of the signal variety or can be ordinary illuminating flares. The firearm is constructed in a rather substantial manner so that considerable mass is employed whereby the recoil of discharge of a projectile will be substantially absorbed by the mass of the firearm. The barrel of the firearm is substantially shorter than the flares adapted for use therein. The walls of the flares therefore are constructed with sufficient strength that they will serve as an auxiliary or detachable barrel for the firearm which can be removed from the firearm as soon as the projectile has been discharged from the cartridge casing of the flare. The walls of the flare do not distort when the propelling charge provided therein is exploded so that the cartridge casing can be readily removed either through the muzzle of the firearm or through the breech thereof.

A flare of the signal or illuminating type satisfactory for use in the firearm of this invention is disclosed in the patent to L. L. Driggs, Jr. et al., No. 1,947,834, patented Feb. 29, 1934.

The flare disclosed therein, and shown in Figure 5, is adapted to be loaded into a fire-

arm through the muzzle end thereof. The flare consists of a cartridge casing 80 of sufficient strength to withstand without distortion the expansion of the gases of a propelling charge 81 provided in the base 82 of the cartridge casing. The base 82 is provided with an annular groove 83 that is adapted to be engaged by the latch-extractor 51 of the firearm (as shown in Figure 6). The forward end of the cartridge casing 80 is provided with a detachable wall 84 that is removed upon expelling the shell 85 provided within the cartridge casing 80. A firing cap 86 is provided in the base 82 and is adapted to set off or explode the propelling charge 81. The propelling charge 81 forces the shell 85 from the cartridge casing 80 and thus from the firearm itself, the cartridge casing 80 remaining in the firearm after the shell 85 has been discharged therefrom.

The cartridge casing 80 therefore provides a detachable auxiliary barrel that extends a substantial distance beyond the permanent barrel of the firearm, and is capable of performing this function because the wall of the auxiliary barrel 80 is of sufficient strength to withstand the explosion of the propelling charge without distorting to thereby permit the auxiliary barrel to be slidably discharged from the permanent barrel when released by the latch-extractor 51.

The shell 85 includes a delayed action fuse 87 provided in the base thereof and an igniting charge 88 adapted to ignite the flare 80. The igniting charge 88 also provides a propelling charge to expel the flare 80 and the parachute 90 attached thereto from the shell 85 after a predetermined time as determined by the delayed action fuse 87. A suitable detachable end wall 91 closes the end of the shell 85.

The cartridge casing and the shell contained therein is more fully disclosed and described in the aforementioned patent and is only representative of the type of flare or projectile that is adapted for use in the firearm of this invention.

Figures 5 to 10 inclusive disclose the firearm of this invention as used in combination with a muzzle loaded flare as just described.

Figures 12 to 15 inclusive disclose the manual manipulation of the firearm of this invention for loading, firing and unloading a muzzle loaded projectile as just described, which operation may be performed by the use of only one hand.

When the firearm of this invention is used in combination with muzzle loaded flares, or cartridge casings, the cartridge casing 80, or flare, previously described is preferably placed in a rack 92 which can be mounted upon any suitable wall of a craft. The flares 80 are disposed in the rack 92 with the annular groove 83 in the uppermost position so that it will be the first portion to enter the barrel 13 of the firearm when placed upon the cartridge casing or flare 80. Preparatory to picking up a flare or cartridge casing through the muzzle of the barrel 13 the button 67 on the pin 62 is pressed with the index finger (as shown in Figure 12) to move the small portion 63 of the pin 62 adjacent the latch-extractor 51, thereby permitting the ear 54 to enter the interior of the barrel 13. The muzzle of the barrel 13 is then forced down upon the cartridge casing 80 (as shown in Figure 13) until the groove 83 in the cartridge casing 80 is engaged by the latch-extractor 51 (as shown in Figure 6). The firearm can then be discharged in conventional manner (as shown in Figure 14) or it can be

placed within the mount (shown in Figure 11) to discharge the flare therethrough.

After the firearm has been discharged the button 66 is pressed by the thumb of the hand holding the firearm (as shown in Figure 15) so that the enlarged portion 64 of the pin 62 engages the latch-extractor 51 and forces the same downwardly against the torsion spring 66 to place the upper face of the ear 54 in flush relationship with the inner wall of the barrel 13 (shown in Figure 7) whereby the cartridge casing 89, now emptied of its shell 85, can be dropped from the firearm through the muzzle end thereof.

As long as the firearm is to be used with muzzle loaded flares there is no particular need for operating the latch 17, since this is merely to permit opening of the breech of the firearm.

Figures 1 to 4 inclusive show the same firearm for use in combination with a breech loaded type of fixed ammunition or flare, while Figures 16 to 20 inclusive disclose the manual manipulation of the firearm when using breech loaded ammunition for operating the firearm by the use of only one hand.

The breech loaded type of fixed ammunition or flare 93 is provided with an annularly extending rim 94 (shown in Figure 1) that is adapted to seat within an annular groove 95 provided in the end wall of the barrel 13 adjacent the breech wall 16. The flare 93 is thus retained in the annular groove 95 between the barrel 13 and the breech wall 16 as is conventional with breech loaded fixed ammunition.

In order to use the breech loaded flares 93 they are preferably retained within a rack 96 that may be secured to any craft upon which the firearm is to be carried. When the firearm is to be loaded the latch 17 is forced upwardly with the thumb of the hand (shown in Figure 16) thereby tilting the barrel 13 forwardly (shown in Figure 17). A flare 93 can then be inserted through the breech of the barrel 13 by moving the barrel upwardly over a flare (shown in Figure 17). After the flare is removed from the rack 96, by sliding the same therefrom, the firearm is then given a quick upwardly rotating motion so that the breech of the firearm will close and the latch 17 will move over the strike 20 and engage the rear face thereof to lock the breech, this motion being shown in Figure 18.

The firearm can then be manipulated in conventional manner to discharge the shell from the cartridge casing (shown in Figure 19).

After the shell has been discharged from the cartridge casing the latch 17 is then released with the thumb (shown in Figure 16) to break the breech of the gun. At this time the tongue 57 upon the extension 15 engages the downwardly extending portion 56 of the latch extractor 51 to move the same rearwardly (as shown in Figure 4). The upwardly extending ear 54 engages the rim 94 of the flare casing 93 to extract the flare casing through the breech of the barrel 13. The firearm can then be turned upside down, that is, with the breech pointing downwardly (as shown in Figure 20) so that the flare casing 93 will drop through the breech of the firearm.

When the firearm is used under certain circumstances, such as upon aircraft, it may be that it is desired to fire the firearm without removing gloves from the hand that is operating the firearm. Under such circumstances it may also be desirable to place the firearm in a mount such as that disclosed in Figure 11 to permit its operation more readily with a gloved hand.

As shown in Figure 21, the firearm is being mounted within a mount such as that disclosed in Figure 11 by a motion that consists of a combined forward and rotating motion to bayonet the barrel 13 within the mount and to lock the same thereto by means of the latch 14. To open the breech of the firearm the portion of the gloved hand between the thumb and index finger is forced under the latch 17 whereby it is moved upwardly and the frame of the gun will pivot downwardly about the pivot pin 14 to open the breech of the barrel 13. A breech loaded type of flare can then be inserted through the breech of the barrel 13 (as shown in Figure 23) after which the frame of the firearm is closed in conventional manner (as shown in Figure 24). After firing the flare the breech of the firearm can be opened in the same manner as shown in Figure 22 whereupon the latch extractor 51 will extract the flare sufficiently far to permit grasping thereof between the thumb and fingers of the gloved hand for removal of the spent flare. The firearm can then be removed from the mount (as shown in Figure 25) upon releasing the latch 14 from engagement with the mount.

From the foregoing description it will readily be understood that the firearm of this invention is capable of operation by the use of only one hand. Also, that the firearm can be used either as a muzzle loaded device or as a breech loaded device without interfering with the operation of the firearm when used with either breech loaded or muzzle loaded fixed ammunition. It is also readily apparent that a single mechanism produces the double function of retaining a muzzle loaded fixed ammunition within the barrel of the firearm and releases the same therefrom as well as extracting a breech loaded type of fixed ammunition. The construction and arrangement of the firearm of this invention considerably widens the use of the firearm since it can be used with either muzzle loaded or breech loaded fixed ammunition regardless of which is being carried at the particular time and is readily interchangeable for use with either type of ammunition without making a single alteration in the construction of the firearm. There is no shifting over of constructions of the firearm when used with either ammunition but it is always available for either use.

It is also readily apparent that the applicant has provided a firearm wherein a particular type of ammunition, such as that wherein the walls have sufficient strength to resist deformation by the expelling charge therein, is usable for easy discharge of the ammunition after firing thereof, and which ammunition provides an auxiliary or detachable barrel for the firearm regardless of whether the ammunition is of the muzzle loaded or breech loaded variety.

While the construction and arrangement disclosed herein shows a preferred form of the invention, yet it is to be understood that the construction of the device can be modified substantially without departing from the spirit of the invention, and that all such modifications as fall within the scope of the appended claims are intended to be included herein.

Having thus fully described my invention what I claim as new and desire to secure by Letters Patent is:

1. A firearm for discharging fixed ammunition having a barrel constructed and arranged to receive interchangeably muzzle loaded or breech loaded fixed ammunition, a breech wall for said

barrel movable relative thereto to permit extraction of breech loaded ammunition, and means for retaining muzzle loaded fixed ammunition within said barrel against said breech wall when firing the same and releasing said ammunition when spent and for extracting breech loaded fixed ammunition.

2. A firearm for discharging signal flares having a barrel constructed and arranged to receive interchangeably muzzle loaded or breech loaded fixed ammunition, and a single mechanism for retaining and releasing muzzle loaded ammunition for discharge through the muzzle and for extracting breech loaded ammunition.

3. A firearm adapted to receive interchangeably breech loaded or muzzle loaded fixed ammunition through breech or muzzle thereof which consists of a frame adapted to be hand grasped, a permanent barrel pivoted to said frame constructed and arranged to receive fixed ammunition by muzzle loading and to pivot upon said frame to receive fixed ammunition by breech loading, latch means engaging either fixed ammunition when in said barrel, and means for latching said barrel in closed position upon said frame, both of said latch means being so disposed upon the firearm that operation of both latch means can be accomplished by the fingers of the hand grasping the frame.

4. A firearm having a barrel for interchangeably receiving muzzle loaded or breech loaded fixed ammunition loaded through the muzzle or breech thereof, a single mechanism for engaging either fixed ammunition in said bore, and independent means for selectively actuating said mechanism to release muzzle loaded ammunition or extract breech loaded ammunition.

5. A firearm adapted to receive fixed ammunition interchangeably through the muzzle or breech thereof which consists of a frame, a smooth-bore cartridge holder, means pivotally mounting said holder upon said frame, a latch-extractor extending into said bore to retain muzzle loaded ammunition therein and extract breech loaded ammunition therefrom, separate and independently operable means for actuating said latch-extractor to release muzzle loaded ammunition and extract breech loaded ammunition, and means for latching said cartridge holder in firing position upon said frame.

6. A firearm adapted to receive fixed ammunition interchangeably through the muzzle or breech thereof which consists of a frame, a smooth-bore cartridge holder, means pivotally mounting said holder upon said frame, a latch-extractor extending into said bore to retain muzzle loaded ammunition therein and extract breech loaded ammunition therefrom, means movable separately from said latch-extractor for actuating said latch-extractor to release muzzle loaded ammunition and extract breech loaded ammunition, and

means for latching said cartridge holder in firing position upon said frame, said separately movable means and said cartridge holder latching means being positioned upon the firearm for operation thereof by the fingers of one hand of a person operating the same.

7. In a combination muzzle loaded or breech loaded firearm, a frame, a barrel, means pivoting said barrel on said frame, means for latching said barrel in closed position upon said frame, a latch-extractor slidably disposed adjacent said barrel having means extending into said barrel to engage fixed ammunition placed therein, means urging said latch-extractor into said barrel to engage fixed ammunition loaded therein through the muzzle of said barrel, means to disengage said latch-extractor from engagement with muzzle-loaded fixed ammunition and means for sliding said latch-extractor longitudinally of said barrel to engage fixed ammunition loaded through the breech of said barrel to extract the breech loaded ammunition from said barrel.

8. A firearm comprising a frame having a breech wall, a barrel disposed adjacent said breech wall for providing a cartridge chamber constructed and arranged to receive breech loaded or muzzle loaded fixed ammunition, means pivotally mounting said barrel upon said frame, means for locking said barrel adjacent said breech wall, extracting means slidably mounted adjacent said barrel movable longitudinally thereof for extracting fixed ammunition therefrom loaded through the breech of said barrel, and means for causing said extracting means to move transversely of said barrel for urging a part of said extracting means into said barrel to engage and retain fixed ammunition therein loaded through the muzzle thereof and for releasing said extracting means from the muzzle loaded ammunition.

9. A firearm comprising a frame having a breech wall, a barrel disposed adjacent said breech wall for providing a cartridge chamber constructed and arranged to receive breech loaded or muzzle loaded fixed ammunition, means pivotally mounting said barrel upon said frame, means for locking said barrel adjacent said breech wall, extracting means slidably mounted adjacent said barrel movable longitudinally thereof for extracting fixed ammunition therefrom loaded through the breech of said barrel, means for causing said extracting means to move transversely of said barrel for urging a part of said extracting means into said barrel to engage and retain fixed ammunition therein loaded through the muzzle thereof, and means for moving said extracting means transversely of said barrel to release the muzzle loaded fixed ammunition so that the same can slide forwardly through the muzzle of said barrel.

EDWIN H. JOHNSON.
